his Attorney.

UNITED STATES PATENT OFFICE.

JOSEPH F. READ, OF ST. LOUIS, MISSOURI.

AUTOMATIC PRIMING DEVICE.

1,411,183.

Specification of Letters Patent. Patented Mar. 28, 1922.

Application filed July 10, 1919. Serial No. 309,835.

To all whom it may concern:

Be it known that I, JOSEPH F. READ, a citizen of the United States, and residing at St. Louis, Missouri, have invented a new and useful Improvement in Automatic Priming Devices, of which the following is a specification.

This invention relates to automatic priming devices for gas engines and more particularly for the gas engines of automobiles.

The starting of a gas engine is facilitated by delivering a priming charge to the engine intake at starting. This is not only advantageous where the engine is started by hand crank but also where the engine is started by motor cranking for in such a case the motor and the battery will be saved considerable wear and tear if the starting is rendered an easy matter. The difficulty, however, with hand priming devices is that the rich mixture is liable to be delivered too long so that the engine will not only fail to properly start, but the starting will, in fact, be retarded.

One of the objects of this invention, therefore, is to provide a primer for gas engines which is adapted to automatically deliver a priming charge when the engine is started, as distinguished from a continuously flowing charge of rich mixture cut off by hand.

Further objects will appear from the detail description taken in connection with the accompanying drawing in which:

Figure 1 is a side elevation partly in section of a part of an automobile, its engine and the fuel supply tank, showing the primer embodying this invention;

Figure 2 is substantially full size front elevation of the priming device;

Figure 3 is a view similar to Figure 2, but showing the parts in a different position;

Figure 4 is a section on the line 4—4, Figure 2; and

Figure 5 is a detail section showing the automatic cut off valve.

Referring to the accompanying drawing and more particularly to Figure 1, 1 designates a gas engine of well known construction which is mounted on the chassis 2 of an automobile, the engine being provided with an intake manifold 3 to which is connected a carburetor 4 and with an exhaust manifold 5. The chassis has mounted thereon a fuel tank 6 which is, in this case, mounted under the front seat 7, and there is also provided the usual automobile dash 8 which

may constitute the instrument board as is usual in some types of automobiles. The fuel tank is connected to supply fuel to the carburetor by a fuel pipe 9. The engine is provided, of course, with the usual starting crank 10, although it may be provided with a motor operated starter. The parts so far described may be of usual construction and further detail description thereof is, therefore, unnecessary.

The priming device embodying this invention is adapted to be mounted on the dash 8 so as to be in full view of the driver. It comprises a base plate 11 which has mounted thereon a flanged ring 12, the flange 13 of which extends over the plate and has a threaded connection therewith at the outer circumference as shown at 14. A gasket 15 is interposed so as to form a tight joint. A knurled ring 16 is threaded onto an enlarged annular shoulder 17 of the ring 12 and has a flange 18 for clamping a glass plate 19 against the ring 12, a gasket 20 being interposed to form a tight joint. The ring flange 16 and plate 11 are perforated as shown at 21 to receive screws 22 for mounting the device on the dash 8. There is thus formed a case or reservoir which is fluid tight and which is adapted to be mounted on the dash of the automobile in order that it is in full view of the driver.

Mounted on the base plate 11 is a cylinder 23, this cylinder being secured in position in any suitable manner as by brazing, welding or soldering the same in place. The bore of the cylinder has an outlet 24 connecting with a coupling 25 which has a fluid tight joint connection with the base plate. The inner end of the outlet 24 has a cone-shaped seat 26 while adjacent the seat is a perforation 27 opening into the space in the casing. A pipe 28 is attached to the side of the cylinder opening therein at 29 and has its lower end extending downwardly to nearly the bottom of the casing. Movably mounted in the cylinder is a piston 30. This piston has a stem 31 passing through a plug 32 threaded into the end of the cylinder and mounted on its lower end is a cork float 33. In order to secure this float in position, the end of the stem 31 may be threaded as shown at 34. The piston 30 is in the form of a metallic cup to which the stem 31 is suitably secured, and in this cup is a filler 35 of cork projecting axially beyond the cup and substantially flush circumferen-

tially therewith so as to form not only a packing, but also a valve seat adapted to cooperate with the conical seat 26.

The coupling 25 is connected by a pipe 36 with an intake manifold, the connection being made by the usual form of couplings and by a plug 37 screwed into the intake manifold. The lower end of the casing has a like coupling 38 connected by a pipe 39 with the fuel tank 6 which as shown is located below the level of the device on the dash. The coupling 25 has a perforation 40 extending therethrough and communicating with the atmosphere for a purpose to be hereinafter described.

Assuming the parts to be in the position shown in Figures 2 and 4, in which the casing, which forms an auxiliary fuel reservoir as hereinafter described, is empty and in which the float 33 rests upon the bottom of the reservoir, at which time the piston 30 will be in a position to uncover the ports or the openings 27 and 29, the device will now be in a position for priming the engine when the same is started. It will be noted, in this connection, that the port 29 leading to the pipe 28 is larger than the port 27 leading to the interior of the casing or reservoir. Furthermore, the port or opening 40 leading directly to the fuel pipe 36 connected to the intake is very small, that is, considerably smaller than the port 27.

When the engine is started by hand or by motor, the pistons during their intake stroke will cause an upward flow of the gases through the carburetor and intake manifold into the engine cylinders. This flow of the gases past the outlet of the pipe 36 in the intake manifold will cause by induction, a reduction of the pressure below atmospheric pressure inside of the pipe 36. This will cause a reduction of pressure inside of the cylinder 23, and since the cylinder is in communication with the interior of the casing or reservoir through the ports 27 and 28, there will be caused a reduction of pressure inside of this casing or reservoir. Of course, there is a slight inflow of atmospheric air through the port 40 into the pipe 36, but this is not sufficient to prevent a reduction of the pressure inside of the cylinder and the reservoir. As the pressure inside of the cylinder and reservoir falls below atmospheric pressure, the fuel will rise in the pipe 39 and will accumulate in the reservoir. As soon as the level of the fuel reaches the inlet to the pipe 28, due to the fact that this inlet is now closed by the fuel and due to the fact that the port 27 is smaller than the port 29, the pressure inside of the cylinder will drop below the pressure inside of the reservoir; accordingly, the fuel will now rise in the pipe 28 and will flow through the cylinder and its outlet 24 into the pipe 36 and into the intake manifold. This flow of the fuel is ac-

companied by a flow of air so that the fuel will become atomized and slightly carbureted before passing into the intake manifold and so that the charge is thrown in an atomized condition into the intake manifold where it becomes further atomized and as it is discharged into the flow of gases upwardly through the intake manifold, the result is that a rich mixture will be discharged into the engine cylinders so as to prime the engine when starting. As this operation proceeds, the level of the fuel will rise in the reservoir carrying the float with it, and therefore, moving the piston on it upwardly. This piston passes successively and closes the ports 29 and 27 until the facing 35 engages the seat 26 at which time, both ports 29 and 27 will be closed and the outlet will be completely closed from communication with the cylinder and the reservoir. The flow of the rich mixture to the intake manifold will, therefore, cease. In view of the fact, however, that there will be a rich mixture or atomized fuel inside of the pipe 36 when the piston closes the outlet 24, the port 40 is provided so that the inflow of air will cause this rich mixture in the pipe 36 to be fully discharged into the intake manifold. Thereafter the supply of rich mixture to the engine will be entirely cut off and the engine will now operate in the usual way, drawing its supply of carbureted air from the carburetor.

The parts will remain in the position shown in Figure 3 with the supply of rich mixture entirely cut off until the engine again stops; at this time, atmospheric pressure is again established in the pipe 36 and accordingly in the cylinder and the reservoir; consequently, the level of the liquid will drop inside of the reservoir, causing the float and its attached pistons to drop and assume the normal positions shown in Figures 2 and 4, with the ports 29 and 27 again opened to the interior of the reservoir and the parts are then again in position for operation.

If it should happen that the engine back fires, which is usually caused by too lean a mixture, at that time, atmospheric pressure will not only be established in the pipe but rather increased; accordingly, the piston is forced down momentarily, thereby opening the ports 29 and 27 and consequently causing the supply of a charge of rich mixture to the engine cylinders, thereby reestablishing normal conditions and stopping back firing.

It will, therefore, be seen that this invention accomplishes its objects. When the engine is started, the device operates automatically by the flow of the gases at the engine to automatically deliver a limited priming charge from the main supply to the engine when the engine is started; and the flow of the priming fuel is terminated after a predetermined quantity of priming fuel is de-

livered or after a predetermined fuel flow. Accordingly, the device is entirely automatic in its action in that only a limited priming charge is automatically delivered as distinguished from a continuous flow which must be cut off manually by the driver. Not only is this priming charge delivered automatically when the engine is started, but it is also delivered during abnormal operation 10 of the engine, as when the engine back fires as heretofore described. The device is so constructed that it can be placed on the dash of the automobile in full view of the driver and on account of the transparent plate, the 15 operation can not only be observed but it can be observed whether there is in fact fuel in the fuel tank 6.

It is obvious that various changes may be made in the details of construction without departing from the spirit of this invention; 20 it is, therefore, to be understood that this invention is not to be limited to the specific construction shown and described.

Having thus described the invention, what 25 is claimed is:

1. A primer for gas engines, comprising a source of fuel supply, means for supplying fuel to the engine, and means co-operating therewith including an auxiliary fuel reservoir in continuous communication with said supply and operating upon the 30 flow of gases at the engine, adapted to automatically deliver a measured priming charge when the engine is started.

2. A primer for gas engines, comprising a source of fuel supply, means for supplying fuel to the engine, and means co-operating therewith including an auxiliary fuel reservoir in continuous communication 40 with said supply and operating upon the flow of gases at the engine, adapted to automatically cause a flow of priming fuel to the engine and thereafter terminate the flow.

45 3. A primer for gas engines, comprising a source of fuel supply, means for supplying fuel to the engine, and means co-operating therewith including an auxiliary fuel reservoir in continuous communication 50 with said supply, and operating upon the flow of gases at the engine, adapted to automatically deliver a predetermined quantity of priming fuel to the engine.

4. A primer for gas engines, comprising a source of fuel supply, means for supplying fuel to the engine, and means co-operating therewith including an auxiliary fuel reservoir in continuous communication 55 with said supply, and operating upon the flow of gases at the engine, adapted to automatically deliver priming fuel to the engine for a predetermined period.

5. A primer for gas engines, comprising a source of fuel supply, means for supplying fuel to the engine, and means co-

operating therewith including an auxiliary fuel reservoir in continuous communication with said supply, and operating upon the flow of the gases at the engine, adapted to automatically deliver priming fuel to the 70 engine when starting and terminate the flow after the engine has started.

6. A primer for gas engines, comprising a source of fuel supply, a fuel pipe adapted for connection to the engine intake, means 75 including an auxiliary fuel reservoir in continuous communication with said supply and operating upon the flow of gases in the intake adapted to automatically deliver priming fuel to said pipe, and means for automatically terminating the fuel flow.

7. A primer for gas engines, comprising a source of fuel supply, a fuel pipe adapted for connection to the engine intake, automatic means including an auxiliary fuel reservoir 85 in continuous communication with said supply and operating upon the flow of gases in the intake adapted to deliver priming fuel to said pipe, and means operating after an interval adapted to terminate the 90 fuel flow.

8. A primer for gas engines, comprising, a fuel pipe adapted for connection to the engine intake, automatic means operating upon the flow of gases in the intake adapted 95 to deliver priming fuel to said pipe, and means operating after a predetermined flow adapted to terminate the fuel flow.

9. A primer for gas engines, comprising, a fuel reservoir, a pipe connected thereto 100 and arranged for connection to the engine intake, together with means including an auxiliary fuel reservoir in continuous communication with said supply adapted upon the flow of gases in the intake to automatically deliver a measured priming charge to the intake when the engine is started.

10. A primer for gas engines, comprising, a fuel reservoir, adapted for permanent connection to the source of fuel, a pipe connected to said reservoir and arranged for connection to the engine intake, together with means adapted upon the flow of the gases in the intake to automatically deliver a measured priming charge to the intake 110 when the engine is started.

11. A primer for gas engines, comprising, a fuel reservoir, adapted for permanent connection to the source of fuel, a pipe connected to said reservoir and arranged for 120 connection to the engine intake, together with means adapted upon the flow of the gases in the intake to automatically cause a flow of fuel from the source to said reservoir and deliver a measured priming charge 125 from said reservoir to the intake when the engine is started.

12. A primer for gas engines, comprising, a fuel reservoir arranged for permanent connection to a fuel source, a pipe connected 130

to said reservoir and arranged for connection to the engine intake, automatic means adapted upon the flow of gases in the intake to deliver priming fuel to the intake, and means adapted after a flow interval to automatically terminate the flow.

13. A primer for gas engines, comprising, a fuel reservoir arranged for connection to a fuel source, a pipe connected to 10 said reservoir and arranged for connection to the engine intake, automatic means adapted upon the flow of gases in the intake, to cause a flow of fuel from the source to said reservoir and to deliver priming 15 fuel from said reservoir to the intake, and means adapted after a flow interval to automatically terminate the flow.

14. A primer for gas engines, comprising, a fuel reservoir arranged for connection 20 to a fuel source, a pipe connected to said reservoir and arranged for connection to the engine intake, automatic means adapted upon the flow of gases in the intake, to deliver priming fuel to the intake while 25 the fuel from the source accumulates in the reservoir, and means operating after accumulation of fuel in said reservoir adapted to automatically terminate the delivery of the priming fuel.

30 15. In an automobile having a dash, a fuel supply, and an engine provided with an intake, a primer, comprising, a device mounted on the dash and having a pipe connection to the fuel supply, a pipe connecting said device to the intake, and means 35 in said device, adapted to automatically deliver a measured priming charge to the intake when the engine is started.

16. A primer for gas engines, having a main source of fuel supply, comprising, an auxiliary fuel reservoir in continuous communication with the main source, automatic means operating upon the flow of gases at the engine, to deliver a supply of fuel to said reservoir, and to deliver a measured priming charge from said reservoir to the engine.

17. A primer for gas engines, having a main source of fuel supply, comprising, automatic means, operating upon the flow of 50 gases at the engine, adapted to deliver a measured priming charge of fuel from the main source to the engine.

18. A primer for gas engines, having a main source of fuel supply, comprising, 55 automatic means, operating upon the flow of gases at the engine, and including an auxiliary fuel reservoir in continuous communication with the main source, adapted to deliver a measured priming charge of fuel 60 from the main source to the engine.

19. A primer for gas engines, having a main source of fuel supply, comprising, an auxiliary fuel reservoir in continuous communication with the main source, automatic 65 means operating upon the flow of gases at the engine, to deliver a supply of fuel to said reservoir, and means operating in accordance with the level of the fuel in said reservoir, adapted to deliver a measured 70 priming charge of fuel from said reservoir to the engine.

In testimony whereof I affix my signature this 23 day of June, 1919.

JOSEPH F. READ.
